METHOD FOR PRODUCING MINERAL WOOL
IN PELLET FORM

Edward F. Cusick, Des Plaines, Ill.

Application December 29, 1941, Serial No. 424,804

1 Claim. (Cl. 154—28)

This invention relates to the art of producing and treating mineral wool so that the same is delivered in pellet form without resort to the several steps heretofore practiced after production of the mineral wool in its substantially straight fibre form.

Hence, the main object of the invention is to provide a very simple and efficient apparatus and method for accomplishing the aforesaid production of the mineral wool in pellet form by a continuous treatment which includes the primary step of producing the mineral wool and delivering it to a means which effects the discharge of air and steam initially admixed with and which serve to maintain the wool in suspension as the same enters the portion of the apparatus which converts the same into pellets.

In the production of mineral wool substantially every fibre thereof has attached to it, at one end, a grain of sand. The size and weight of these grains of sand vary appreciably and, obviously constitute the heaviest end of the fibre and must be detached therefrom and sifted out of or otherwise eliminated from the mass of fibre before the latter is marketable. The detachment of the sand grains has been effected heretofore during the mechanical operations whereby the fibre is converted into pellet form, this operation being followed in some instances by a sifting operation to remove the sand.

The present method of converting the mineral wool into pellets causes a loss of a very appreciable percentage of the wool due to a comminution of fibres which takes place, the comminuted fibres constituting waste which is also eliminated during the sifting operation where the latter is resorted to. If omitted, the product admixed with sand and waste is very inferior to that from which the sand and waste is eliminated.

The method now generally practiced, as aforesaid, to convert the fibres from substantially straight to pellet form, causes the pellets to be comparatively compact, whereas it is desirable that they shall be lacking in compactness to a very appreciable degree in order that a pound thereof shall occupy appreciably greater volume of space than the pellets produced mechanically by said commonly practiced method.

Hence, a very important object of the present invention is to provide a method and apparatus as aforesaid which will effect detachment of the sand grains from the fibres and reduce the latter to pellet form of a type appreciably less compact than the pellets produced by the mechanism now commonly used for that purpose and

wherein the production of the mineral wool, its conversion into pellet form and the detachment of sand grains from the fibres constitutes a single continuous operation which is followed only by the sifting operation to eliminate the sand grains from the mass precedent to packaging the latter.

A suitable embodiment of an apparatus adapted to carry out the method of this invention and which is constructed in accordance with the invention is illustrated in the accompanying drawings wherein

Fig. 1 is a diagrammatic view in elevation of an apparatus, constructed in accordance with the invention, used for producing mineral wool in pellet form.

Fig. 2 is a vertical, longitudinal, sectional view illustrating a modified form of the mineral wool receiving tube of the apparatus shown in Fig. 1.

Fig. 3 is a vertical, transverse, sectional view of the tube of Fig. 2 taken on the line 3—3 of Fig. 2.

Fig. 4 is a fragmentary bottom plan view of the tube of Fig. 2.

Fig. 1 of the drawings includes a fragmentary side elevation of a furnace, 1, wherein rock is melted for discharge from the spout 2, a stream of the molten rock being indicated as flowing from said spout.

The flowing stream of molten rock passes the discharge end of a pipe 3 which is suitably connected, in a conventional manner, with a source of supply of steam under customary high pressure. The steam discharging from said pipe impinges against the stream of molten rock and converts the latter into mineral wool in a well-known manner.

Opposed to the discharge end of the steam ejector pipe 3, is the larger end of a truncated cone-shaped tube 4 into which the mineral wool admixed with steam is projected. The smaller end of said tube 4 is connected by means of a pipe 5 with the suction or intake port of a blower 6, the discharge port of which is connected by means of a pipe 7 with the so-called "cyclone chamber" 8 of a conventional type dust collector or an equivalent thereof as hereinafter set forth. The latter includes the usual damper-controlled discharge dome 10 for discharge of a large part of the fluid portions of the product delivered into the said cyclone chamber, some of said fluid portions being discharged with the solids from the discharge spout 11 of the cyclone chamber and, if desired, through the pipe 12 connected with the latter, thus to effect delivery of the said solids

into a suitable receptacle such as the sifting mechanism for effecting elimination of sand.

Following the sifting operation, the wool is discharged from the last-named apparatus to suitable packaging apparatus, the latter and the said screening apparatus being omitted from illustration as constituting no part of the present invention.

The capacity of the blower 6 must be sufficient to maintain a partial vacuum at the intake end of the tube 4, so that none of the mineral wool may be discharged with the steam into atmosphere around said intake. It is obvious that in this manner a rapid flow of fluid, comprising mixed steam and air, is effected and maintained through the tube 4, the mineral wool being carried in suspension by said fluid to and through the blower and into the cyclone chamber of the dust collector.

The blower is preferably so constructed that an arcuate space is left between the outer edges of the fan blades and the surrounding wall of the blower casing of sufficient width to prevent any grinding of the mineral between said wall and the fan blade edges.

During travel of the fibres in suspension, as aforesaid, through the tube 4 and piping connecting the latter with the blower, the said particles attached to the fibres will remain disposed at the rear ends of the latter like spiders at the ends of their web-strings during migration. This may be true also after the fibres enter the blower casing wherein they are projected radially against the arcuate wall thereof and are partially collapsed or distorted by impact followed by a rolling along said wall until they are disposed into the cyclone chamber and projected against the circumferential wall of the latter where the said rolling and consequent curling operation is continued so that said fibres are delivered in a loosely curled pellet form from the discharge spout of said dust collector.

The impact aforesaid is believed to effect detachment of the sand grains from the fibres but this may occur in part during contact of the fibres with the circumferential wall of said cyclone chamber, the fibres being delivered from the dust collector free of the sand grains.

During the period of flow of fluid, as above described, the steam condenses and it is probable that the fibres then carry a film of moisture. It is quite obvious that the air admixed with the steam is saturated with moisture and it is probable that the film of moisture carried by the fibres increases their weight appreciably and may have an appreciable influence on the results attained. All moisture content of the wool appears to be eliminated by the time that it is discharged from the dust collector or after it has undergone the sifting operation.

The diametric dimensions and length of the tube 4 may be varied to meet the particular conditions of each installation, and the dust collector may be disposed otherwise than vertically.

A tube 4 which is ten to twenty feet long and about four or five feet in diameter at its intake end and two feet in diameter at its discharge end, will be suitable for practically all installations.

In place of the truncated cone-shaped tube 4, other shapes of tubes may be used as exemplified by the tubular member 13 of Fig. 2, the latter being equipped, preferably, with an arched top wall and flat side and bottom walls, the latter being

provided along its side edge portions with perforations 14 opposed to the flanges of angle bars 15 secured to the inner faces of the side walls parallel with and spaced from said bottom wall.

A conveyor belt 16 trained over pulleys 17, suitably actuated, passes over the bottom wall of the tube 13 with its side edge portions traveling in the space between the horizontal flanges of the angle bars 15 and said bottom wall and out of contact with the latter and said flanges.

Adjacent its discharge end, the rear wall portion of the tube 13 is curved upwardly and is provided with a narrow slot 18 through which said belt passes freely.

The suction created by the blower of the dust collector will cause air currents to pass through the perforations 14 and the slot 18 into the tube 13 and in part over the top surface of the belt to prevent any mineral wool settling upon said belt to become disposed in the path of the fluid current of relatively high velocity passing through said tube 13, so that practically none of the mineral wool entering the tube can escape otherwise than through the discharge pipe 19 connected with the intake port of the blower.

The intake end of the tube 13 may be partly choked as shown. Obviously the belt 16 may be arranged to deliver any mineral wool remaining deposited thereupon to a suitable receptacle from which the same may be returned into the tube 13.

The method of this invention will be readily understood from the foregoing, as consisting in effecting continuous rapid travel of the mineral wool from the instant of its creation and while suspended in fluid, through a tubular structure, a blower and a cyclone chamber or the equivalents of the tube, blower and cyclone chamber, so long as said mineral wool while in suspension in said fluids is subjected to violent swirling fluid currents in a confined space as well as being projected against surfaces as aforesaid.

It is well known that the swirling of fluid created within the cyclone chamber of a dust collector will cause the solids suspended in said fluids to move gradually centripetally to the central portion of the said chamber and will be discharged therefrom partly by gravity.

It will be noted that the ducts or pipes leading to the blower 6 and from the latter to the cyclone chamber of the dust collector effect progressive changes in direction of flow of the fluid as does also the dust collector so that the path of travel of the fluid is substantially sinuous.

Obviously the number of changes of direction of such flow of the fluid carrying the wool may be greatly increased in number and character so that appreciable swirling of the fluid will be caused during its travel to and discharge into the said cyclone chamber. Such irregular direction of flow of the fluid will probably cause the mineral wool fibres to be projected repeatedly to duct surfaces during travel and efficiently effect the ultimate result desired to be obtained.

Increase in the normal or customary velocity of flow of the fluid may also be more or less advantageous if for no other purpose than to increase the rate of production of the ultimate product.

While it is preferred to utilize the wool producing steam jet to project the wool into the intake tube, any other fluid pressure means may be utilized to project previously produced mineral wool into said chamber, such other means contemplating the suction flow of air into said tube responsive to operation of the blower 6, as

by disposing a loose mass of the wool into the path of the fluid flowing into the chamber or otherwise causing such wool to become admixed with flow of fluid such as air or steam or a mixture of both.

It will be noted that the pipe discharging into the cyclone chamber is disposed substantially tangential to the circumferential wall of the latter in the conventional manner.

I claim as my invention:

The method of producing mineral wool in pellet form, which consists in subjecting molten mineral to a high velocity steam-jet projected against a stream of said molten mineral in direction transverse of the direction of flow of said stream, disposing the mouth of a duct in the path of the resulting mineral wool fibres and maintaining a flow of air by suction into said mouth continu-

ously through the said duct to a point of discharge and providing obstructions within said duct in the path of said fibres for impingement of the latter against the same to effect a gradually and progressively increasing curling of said fibres during their passage through said duct to the said point of their discharge from the latter, and providing a receiving chamber, for said curled fibres, presenting arcuate surface in the path of the fibres projected from said duct for finally effecting a dense curling thereof whereby said fibres are converted into substantially pellet form, and providing means in said chamber for separating the resulting pellets from the steam and air currents discharged into the said chamber and delivering the said pellets by gravity from the said chamber.

EDWARD F. CUSICK.
